(57) **CLAIM**

The ornamental design for an electric connector with a cable, as shown and described.

DESCRIPTION

FIG. 1 is a top plan view;

FIG. 2 is a front elevation;

FIG. 3 is a left-side elevation;

FIG. 4 is a right-side elevation perspective view;

FIG. 5 is a rear elevation;

FIG. 6 is a bottom plan view rear elevation; and,

FIG. 7 is a perspective view.

The present design is characterized in that a plug-shaped member disposed at one of opposite ends extends axially of the cable the cable, and a socket member disposed at the other end and having lateral eyed-ears does also extend axially of the cable, and in that the eyed-ears lie in a plane which includes the bottom face of the socket member.
